Primary Examiner — Brett Miller*Assistant Examiner* — Jessica M Gebhart(74) *Attorney, Agent, or Firm* — John Rizvi; John Rizvi, P.A.—The Patent Professor®(57) **CLAIM**

I claim the ornamental design for a multi-tier umbrella canopy, as shown and described.

DESCRIPTION

FIG. 1 is a top isometric view of a multi-tier umbrella canopy showing new design;

FIG. 2 is a bottom isometric view thereof;

FIG. 3 is an elevation thereof;

FIG. 4 is a top plan view; and,

FIG. 5 is a bottom plan view thereof.

The broken lines in the figures are for the purposes of illustrating environmental structure and form no part of the claimed design.
